(57) **CLAIM**

The ornamental design for a wind generator as shown and described.

DESCRIPTION

FIG. 1 is a perspective view of a wind generator showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines in FIGS. 1–7 represent portions of the wind generator that form no part of the claimed design. The bottom of the wind generator is rarely seen during use, so the bottom view is omitted
